[57] CLAIM

The ornamental design for an exercise machine, as shown and described.

DESCRIPTION

FIG. 1 is a front and right side perspective view of an exercise machine showing our new design;

FIG. 2 is a left side elevational view, the right side view being a mirror image thereof;

FIG. 3 is a top plan view;

FIG. 4 is a bottom plan view;

FIG. 5 is a front elevational view; and,

FIG. 6 is a rear elevational view.

The handle bar has been shown fragmentarily in FIGS. 3, 5, and 6, for ease of illustration.
